FREQUENCY MODULATION STABILIZATION SYSTEM

André Gabriel Clavier, New York, N. Y., assignor
to International Standard Electric Corporation,
New York, N. Y., a corporation of Delaware

Application March 20, 1947, Serial No. 735,961

4 Claims. (Cl. 179—171.5)

1

This invention relates to the frequency stabilization of systems of the type in which pulses, which may be modulated in a given characteristic in accordance with the instantaneous amplitudes of a signal to be transmitted, are used to frequency modulate the carrier wave.

Various systems, single and multichannel, have been proposed, as for example, in my copending application A. G. Clavier, Serial No. 735,960, filed March 20, 1947, for "Frequency modulation communication system," and in which pulses, modulated in a given characteristic, are used to frequency modulate a carrier wave.

An object of the present invention is the provision of means for frequency stabilizing systems of the type to which this application refers.

The above-mentioned and other features and objects of this invention will become more apparent and the invention itself, though not necessarily defined by said features and objects, will be best understood by reference to the following description of the invention, taken in connection with the accompanying drawings, in which:

Fig. 1 is a block diagram of a multichannel transmission system utilizing both time division and frequency division multiplexing, and particularly illustrated as used for cable transmission;

Fig. 2 is a block diagram of a single channel transmission system utilizing intermittently frequency modulated waves; and

Fig. 3 is a set of curves used in describing the operation of the foregoing systems.

The transmission system of Fig. 1 is adapted to handle a relatively large number of different channels. The channels are treated in separate groups, each group being distinguished from the other by being transmitted over a different portion of the entire frequency band employed. These groups will be referred to herein as "group" or "frequency channels." Within each group of frequency channel, multiplexing is accomplished by time division, that is, each group handles a number of signals which are mixed, utilizing the principle of time division, and are then transmitted within the unique portion of the frequency band belonging to said group.

The foregoing will be best understood with reference to Fig. 1 in which only a limited number of groups and a limited number of channels are illustrated for the easier understanding of the operation of the system. A plurality of signal sources 1-18 are divided into, and treated as three groups as follows: sources 1-6 form group A; 7-12 form group B; and 13-18 form group C.

2

These signal sources are used to modulate pulses which may be derived from a common pulse generator 19, feeding into a pulse distributor 20. The pulse distributor 20 feeds the pulses sequentially to lines 21-36. The pulses fed on each of the lines 21-26 are modulated in each of the groups by the signals from a separate one of the sources. For example, the pulses fed along line 21 are modulated by the signals from source 1, 7, 13. Those pulses fed along line 22 are modulated by the signals from sources 2, 8, 14. The pulses along the other lines are correspondingly modulated.

In the specification and the accompanying claims, the terms "modulated" or "modulation" with respect to pulses or pulse trains are used broadly to signify the variation of a characteristic of such pulses or pulse trains in accordance with the instantaneous values of the signal, and are not limited to any specific techniques or apparatus for producing this result. In this connection, the terms "amplitude modulated" or "amplitude modulation" signify such variations with respect to amplitude.

Since the groups A, B and C are similar in operation and in arrangement only group A will be described. Referring now specifically to group A, amplitude modulation of the pulses is accomplished in modulators 27-32, the pulses from lines 21-26 feeding modulators 27-32 respectively and the signal sources 1-6 respectively, also respectively feeding the modulators 27-32. These modulators may be any of various well-known types and may for example, consist of normally blocked amplifiers which are unblocked by the pulses. The outputs from modulators 27-32 which are in the form of trains of amplitude modulated pulses are fed into the A mixer 33 where the trains of pulses are interleaved. Similar arrangements of modulators in groups B and C are provided and the resultant pulse trains are mixed in the B mixer 34 and the C mixer 35. The multichannel amplitude modulated pulse outputs of mixers 33 to 35 are then fed to frequency modulators 36-38 respectively where they are used to frequency modulate the carrier wave energy in oscillators 39, 40 and 41. The frequency bands covered by oscillators 39, 40 and 41 differ somewhat so that said bands while adjacent, do not overlap each other, thereby providing for frequency division between group channels A, B and C as will be more fully described hereinafter.

Since the output of the transmission system of Fig. 1 is to be transmitted by means of cable,

it is preferred to beat down the output of oscillators 39-41 and for this purpose, use is made of an oscillator 42 of a slightly different frequency output than oscillators 39-41. The oscillator 42 is preferably a highly stable oscillator and for this reason is preferably crystal-controlled. The outputs from oscillators 39-41 are fed into mixers 43-45 where they are mixed with the output of oscillator 42 to produce beat output frequencies which are applied from each of the mixers 43-45 to the same transmission medium, which may be a cable 46.

Designating the frequency of oscillator 42 as F_0 , then the frequency of oscillator 39 is preferably $F_0 + \Delta F_1$, that of oscillator 40 is $F_0 + \Delta F_2$, and that of 41 is $F_0 + \Delta F_3$. ΔF_1 , ΔF_2 and ΔF_3 represent three bands of frequencies preferably adjacent each other but not overlapping. The output of mixers 43-45 is ΔF_1 , ΔF_2 and ΔF_3 respectively. For the purpose of center frequency stabilization, each of the oscillators 39-41 is treated separately and in a similar manner. Accordingly only the stabilization of oscillator 39 will be described. In accordance with a feature of the present invention, stabilization is produced by selecting portions of the frequency modulated carrier waves which are not frequency modulated, that is, the portions between those at which the pulses have produced frequency modulation. For the purpose of selecting said portions, the output of oscillator 39 is fed to a pulse controlled amplifier 47 which is periodically blocked by pulses from generator 19 during the time when frequency modulated portions of the output of oscillator 39 occur. Between the time of occurrence of said frequency modulated portions, energy from the output of oscillator 39 is fed via the amplifier 47 to a stabilization mixer 48 in which such energy is mixed with energy from the stable oscillator 42. The resultant beat frequency is fed to an automatic frequency control system 49 which may be for example, in the form of a discriminator, any deviations from the desired beating frequency resulting in a direct current voltage which is sent back to the corresponding modulator 36 for stabilization purposes. Similar equipment similarly operating is likewise provided in each of the group channels B and C.

An understanding of the operation of the foregoing system may be aided by an examination of the curves of Fig. 3 wherein W_1 , W_2 and W_3 represent a portion of the signals from the signal source 1, 2, and 3 respectively. These produce at the output of modulators 27, 28 and 29 pulses P_1 , P_2 and P_3 whose amplitudes vary in accordance with the instantaneous value of the signals of their channels. The pulses P_1 , P_2 and P_3 etc. are interleaved in mixer 33 and are then used to frequency modulate the carrier C (Fig. 3). The carrier C has a given center frequency which is modulated by the pulses P_1 , P_2 and P_3 to produce frequency modulation at the spaced intervals A_1 , A_2 and A_3 , the extent of the frequency modulation varying in accordance with the amplitude of the pulses P_1 , P_2 and P_3 . The modulated carrier wave C is applied to the amplifier 47 which is periodically unblocked so that the portions A_4 and A_5 between the frequency modulated portions A_1 , A_2 and A_3 are selected and fed to the mixer 48 as indicated in curve C1. The wave C1 is then beaten with the carrier wave F_0 from oscillator 42. The resultant beat frequency is then used to produce frequency stabilization in the automatic frequency control system 49. To facilitate synchronization of the receiver for a transmis-

sion system of the type hereinabove described, the pulses of a given channel, for example channel 1, may be provided with a distinctive characteristic, for example a distinctive duration, by suitable means, such as a pulse shaper, to enable selection of these pulses at the receiver, the selected pulses synchronizing distributors at the receiver for proper separation of the various pulse channels, the group channels being preferably first separated by band pass filters.

While I have described frequency stabilization in connection with a multichannel transmission system, it may also be used with single channel systems, for example, as illustrated in Fig. 2. Referring now to Fig. 2, signals from a source 50 are mixed with pulses from a pulse generator 51 in an amplitude modulator 52, which may be similar to those described in connection with Fig. 1, to produce a train of amplitude modulated pulses at its output. This train of pulses is then applied to a frequency modulator 53 where it is used to modulate the frequency of a carrier wave produced in an oscillator 54, the output of the oscillator 54 then being applied to some suitable transmission medium such as for example, an antenna 55. For frequency stabilization purposes, the output of oscillator 54 is likewise fed to a pulse controlled amplifier 56 similar to amplifier 47 of Fig. 1, to pass only those portions of the modulated carrier wave output of oscillator 54 which are not modulated. These selected portions of the output are then applied to an automatic frequency control system 57 to control, as indicated by line 58, the frequency of oscillator 54. The automatic frequency control system 57 may be any suitable system, and may include, for example, a reference oscillator of relatively stable characteristics such as for example, a crystal-controlled oscillator, or simpler forms of automatic frequency control may be employed.

While I have described above the principles of my invention in connection with specific apparatus, and particular modifications thereof it is to be clearly understood that this description is made only by way of example and not as a limitation on the scope of my invention.

I claim:

1. A signal transmission system comprising a carrier wave source, a modulator for frequency modulating said wave solely at spaced intervals thereof leaving unmodulated portions therebetween, means for selecting solely unmodulated portions of the frequency modulated wave after the wave has passed through said modulating means, and means responsive to the frequency of said selected portions for frequency stabilizing said source.

2. A system according to claim 1, further including means for producing a train of pulses, means for amplitude modulating said pulses in accordance with instantaneous values of the signal to be conveyed, and means for applying the amplitude modulated pulses to said frequency modulator to frequency modulate the carrier wave at spaced intervals thereof.

3. A system according to claim 2, wherein the selecting means includes a circuit for coupling the output of said frequency modulator to the frequency stabilizing means, and means controlled by the pulses from the pulse producing means for alternately blocking and unblocking said circuit.

4. A system according to claim 3, including means for normally blocking said circuit and means for applying said pulses to said circuit to

2,468,038

5

periodically unblock said circuit, whereby frequency stabilization occurs only between the modulated intervals of the wave.
